FIG. 2 is a front elevation view.

U.S. PATENT DOCUMENTS

FIG. 3 is a rear elevation view.

562,440 A 6/1896 Vanderall
2,003,657 A 6/1935 Stubblefield
2,600,478 A 6/1952 Campomar

FIG. 4 is a right side elevation view, the left side elevation being a mirror image

FIG. 5 is a top plan view.

FIG. 6 is a bottom plan view; and,

FIG. 7 is a cross section view taken along line 7-7 of FIG. 3. The dominant features of my design reside in the lid's basin, which is triangular shaped. The broken lines in the drawings represent unclaimed environmental subject matter and form no part of the claim.
